IMPULSE TIMER

Arthur J. Kizaur, Cicero, Ill., assignor to General Electric X-Ray Corporation, Chicago, Ill., a corporation of New York

Application July 1, 1941, Serial No. 400,666

21 Claims. (Cl. 200—91)

My invention relates in general to timing mechanism and has more particular reference to a timer for the control of electrical equipment in accordance with time periods determined by electrical impulses, such as sixty cycle alternating current, which occur at a predetermined frequency.

An important object of the present invention is to provide a timer mechanism adapted to maintain an electrical circuit during a precise time period determined by a selected number of impulses in a fluctuating monitoring wave; a further object being to provide apparatus of the character mentioned which, because of its ability to effect precise time control in terms of a selected number of impulses in a fluctuating wave series, is peculiarly adapted for use in controlling the operation of X-ray equipment.

Another important object is to provide control apparatus which performs a time control function in terms of a desired number of impulses of electrical energy comprising a wave fluctuating preferably at constant frequency, the apparatus being conditionable for operation in response to any selected number of impulses within the range of the device.

Another important object is to provide an impulse timer of the character mentioned, including circuit making and breaking means, a motor for actuating the circuit making and breaking means at a predetermined speed under the control of a monitoring wave of electrical energy, which fluctuates or alternates at a predetermined frequency, together with selectively operable mechanism for adjusting the apparatus whereby to actuate the circuit making and breaking means at precise instants during the course of the monitoring wave.

Another important object is to provide apparatus, including a pair of switches and a synchronous motor for closing one switch and thereafter opening the other after the elapse of a time interval determined by the occurrence of a predetermined number of impulses of a fluctuating monitoring wave of electrical energy, including selectively operable conditioning means to determine the number of impulses which occur between the closing of one switch and the opening of the other; a further object being to utilize a continuously operating motor, in combination with novel means for connecting the motor with means for actuating the switches at the beginning of the operating cycle of the control mechanism and breaking the driving connection between the motor and the switch actuating means at the conclusion of the operating cycle of the mechanism;

5 a further object being to provide separate actuating devices for each switch and to provide for adjusting the spacement between the switch actuating devices as a function of the frequency of the monitoring wave in order to constitute the device as a selectively conditionable time control mechanism.

Another important object is to arrange the switch actuating devices in a support frame for adjustable angular displacement about a common axis or center and to utilize rotating means adapted for driving connection with a synchronous motor for the purpose of successively operating the switch actuating devices.

Another important object is to mount one of the switches in fixed position on the frame and to support the other switch on a movable yoke for angular adjustment with respect to the fixed switch; a further object being to utilize turnable cam means having a switch actuating projection or finger which, when the cam is turned by the motor, will successively actuate the angularly displaced switches; a further object being to provide means whereby the cam will be yieldingly held in stand-by position having a fixed angular relationship with respect to the position of the fixed switch so that, when connected to the motor, it will actuate the fixed switch at a predetermined time interval following the establishment of the driving connection between the cam and the motor.

Another important object is to utilize a dog clutch for connecting the motor with the cam so that the connection may be made positively and without slipping at the beginning of the operating cycle of the switch actuating mechanism, a further object being to utilize, as a clutch, a toothed driving wheel or clutch member having a number of teeth selected in accordance with the number of fluctuations of the monitoring wave which occur during one revolution of the clutch member whereby the apparatus may be adjusted to actuate the switches at predetermined corresponding or like points, such as zero energy points, 45 in the fluctuating monitor wave.

Another important object resides in utilizing a non-symmetrical heart cam and a preferably spring biased follower for the purpose of orienting the switch actuating cam to its stand-by position.

50 Another important object is to utilize a synchronous motor for driving the switch actuating mechanism from stand-by position through an operating cycle; a further object being to mount the motor for angular adjustment with respect to the fixed switch in order that the apparatus

may be adjusted to cause the fixed switch to close after commencement of an operating cycle at a desired instant, such as the zero point in the monitoring wave, which preferably is an alternating current wave, whereby to cause the switch to close under minimum load and thereby eliminate arcing at the switch contacts and consequent deterioration thereof; a further object being to calibrate the apparatus so that the shiftable switch may be adjusted only to such spaced positions that the same is opened at the conclusion of the operating cycle of the device at a predetermined point, such as a zero point, in the monitoring wave, to thereby minimize arcing at the contacts of the adjustable switch.

Another important object resides in providing improved switch means, including automatic mechanism for resetting the switches upon the conclusion of an operating cycle so that in stand-by position, one switch, namely, the fixed switch, will be open and the other, or shiftable switch, will be closed when the apparatus is in stand-by position ready to perform a timing cycle.

Another important object is to provide improved switch mechanism comprising a co-operating pair of contact members, each of which may be adjusted to provide fresh contact surfaces from time to time without requiring replacement; a further object being to form one of the co-operating switch members as a cylinder which may be turned and anchored in place to present successive cylinder surfaces in position to contact with the co-operating switch member and thus allow the contacting surface of the cylindrical switch member to be periodically renewed; a further object being to form one of the switch members as a bar supported in a suitable mounting so that both sides of the bar at both ends thereof may be utilized to afford four successively usable switch contact surfaces.

Another important object resides in providing a readily operable selector member, whereby accurately to adjust the spacement of the movable switch with respect to the fixed switch; a further object being to utilize an index panel and a manually movable member adjustable on said panel and drivingly connected with the yoke on which the shiftable switch is carried; a still further object being to provide a marked index plate fastened on the manually movable member in position to co-operate with a gauge mark on the index panel, whereby the setting of the mechanism may be visually indicated always at one place opposite the gauge mark.

These and numerous other important objects, advantages and inherent functions of the invention will become apparent as the invention is more fully understood from the following description, which, taken in connection with the accompanying drawings, discloses a preferred embodiment of the invention.

Referring to the drawings:

Figure 1 is a vertical section taken through an impulse timer embodying my present invention;

Figure 2 is an inverted sectional view taken substantially along the line 2-2 in Figure 1, with the adjustable switch shifted ninety degrees from the position occupied by it in Figure 1;

Figure 3 is a sectional view taken substantially along the lines 3-3 in Figures 1 and 2;

Figure 4 is a sectional view taken substantially along the line 4-4 in Figures 1 and 2;

Figure 5 is a sectional view taken substantially along the lines 5-5 in Figures 1 and 2, the dotted

line position of the shiftable switch being that occupied by it in the Figure 1 showing;

Figure 6 is a perspective view of a switch forming a part of the apparatus illustrated in Figures 1 and 2;

Figure 7 is a sectional view taken substantially along the line 7-7 in Figure 6;

Figure 8 is a perspective view of the under side of the switch shown in Figure 6; and

Figure 9 is a front end view of the timing device.

To illustrate my invention, I have shown on the drawings timing apparatus comprising a pair of relatively shiftable switches 11 and 15 supported in a main frame 17 having a generally cylindrical skeletal portion 19 carrying the switches and a rearwardly extending bracket portion 21 on which is mounted a motor 23, a solenoid 25, and a connection panel 27.

An index plate 29 is secured on the front of the skeletal frame portion 19 and serves to support manually operable indexing means whereby the apparatus may be adjusted or selectively conditioned for operation during a desired time interval.

In the illustrated embodiment, the switch 11 is a normally open switch and the switch 15 a normally closed switch adapted to be successively actuated by switch actuating means 33 driven at synchronous speed by the motor 23 in order to close the switch 11 and then open the switch 15 after an elapsed interval of time determined by the adjusted spacement of the switches and the synchronous speed of the motor 23 which, of course, in turn, is determined by the frequency of the fluctuating current wave which drives it. The switches 11 and 15 are electrically connected together in series in a circuit to be controlled so that in stand-by position the circuit is open at the switch 11. During the operating cycle of the apparatus, the switch 11 is first closed, whereby the circuit being controlled is closed and thus energized, the controlled circuit being opened at the switch 15 and thus de-energized at the conclusion of the operating cycle of the timing device.

While the invention is not necessarily limited to the form of switches employed, I have shown switches particularly well suited to perform the desired circuit controlling function, said switches 11 and 15 each preferably comprising a frame or base 35 of non-conducting material carrying a preferably cylindrical contact member 37 which is secured to said base as by means of a bolt 39.

The base 35 is supported on a sub-frame 41 which includes a pivot pin 43 extending adjacent the base 35 and on which pin is pivotally secured a rockable switch member 45 which is preferably formed of non-conducting material and which carries a switch blade 47 in position to make and break contact with the member 37. The switch blade 47 preferably comprises a bar of conducting material, one end of which extends in a seat 49a formed in the member 45, the other end of the switch blade 47 projecting from the member 45 in position to make contact with the member 37. The member 47 is supported yieldingly in the seat 49a on a bolt 52 having spring means 54 associated therewith, whereby the blade 47 is yieldably supported on the member 45. It will be noted that the switch blade 47, being rectangular, may be inverted in place on the member 45 to present either end in position for engagement with the contact member 37, and also the switch blade 47 may be mounted

with either face in position to form a switch contact surface with the member 37. As a face of the member 41 deteriorates in service, it may be renewed several times merely by inverting the member 41 on the carrier member 45. Likewise, as the active surface of the member 37 deteriorates in service, it may be renewed merely by loosening the bolt 39 and turning the member 37 in place.

The sub-frame 41 of the switch 11 is secured on a seat 49 formed on the frame portion 19 whereby to locate the switch 11 in the assembly. The sub-frame 41 carrying the switch 15, however, comprises an integral part of a yoke 51 having a pair of arms formed with bearings 53 and 55 whereby the same and the switch 15 carried thereon is turnably mounted within the frame portion 19.

To this end, the bearing 55 carries an integral stub shaft 57 extending axially thereof and projecting outwardly of the yoke 51 and being journaled in the plate 29 and extending outwardly thereof. The projecting end of the shaft 57 carries the indexing means 31 which comprises a frame or yoke 61 fixed thereon, said yoke comprising an arm carrying a spring pressed pin 63 in position to sweep circularly across the face of the plate 29 and formed at one end with a detent selectively engageable in any one of a plurality of openings 65 formed in the plate 29 for locking the arm and the yoke 51 to which it is attached in any desired relative angular adjustment determined by the selected opening in which the pin 63 may be engaged. The pin 63 has a manually operable control handle 67 to disengage the pin to release the yoke 61 for turnable adjustment. The yoke 61 carries a disk 69 formed peripherally with an index scale 71 which, in co-operation with an index mark 73 on the plate 29 outwardly of the edge of the disk 69, indicates the adjusted position of the yoke 61 and the yoke 51 throughout the operating range of the device, which is determined by the number of openings 65 in the panel 29. It will be noted that the disk 69 has a perforation to receive the stub shaft 57 and a perforation for receiving the stem 63 so that the disk 69 at all times is fast on the yoke 61, and it may be otherwise secured on the frame by suitable fastening members if desired. The central portions of the disk 69 and also the yoke 61 may, if desired, be enclosed by means of a cover 75 which is held in place by a fastening screw 77 centrally of the cover and which has threaded connection in the end of the stub shaft 57.

By operating the handle 67 to release the pin 63 from the plate 29, the indexing means comprising the frame 61 may turn to shift the yoke 51 and the switch 15 thereon to any desired adjusted position indicated by the scale 71 and index mark 73 and locked in place by releasing the handle 67.

The switch actuating means 33 is driven by the motor 23 which has a shaft 79 formed with a driving pinion 81 which extends within the frame portion 19 in position to drivingly engage a gear 83 which is fast on a shaft 85.

Within the frame portion 19, the pinion 81 and gear 83 are enclosed in a chamber 89 defined by an inwardly extending rim 87, formed on the end wall of the frame portion 19, and a cover 91. The shaft 85 is supported at one end in a bearing 93 formed in the end wall of the frame portion 19 and at the other in the bearing 55. The shaft is normally urged, as by means of a spring 75

95, rearwardly in the frame portion 19, that is to say, toward the left, viewing Figure 1, and has an end projecting rearwardly of the rear wall of the frame portion 19, in position to be engaged by a throwing lever 97 pivoted in the frame extension 21 and drivingly connected with the solenoid 25 so that when the solenoid is energized, the shaft 85 may be projected forwardly from stand-by position against the influence of the spring 95 into switch operating position.

The yoke bearing 55 is journaled on and supported by the shaft 85 which carries a switch resetting flange collar 99 fast on the shaft. The shaft also carries fast thereon a driving gear 101, preferably in the form of a toothed clutch disk, which is supported on a sleeve 103 which is fast on the shaft and which, at one end, forms an abutment for the spring 95, there being roller bearing means 105 interposed between the end 15 of the sleeve 103 and one end of the spring 95, the other end of which bears upon the bottom of a cavity formed in the yoke bearing 55. Journaled on the shaft 85 between the driving gear 101 and the resetting collar 99 is a switch tripping disk 107 formed with a peripheral switch tripping projection or finger 109 and a slot 111 defined by a pair of radial wings 113. Loosely journaled on the sleeve 103 is a cam member 115 comprising an asymmetrical heart shaped disk supported on a collar 117 which is journaled on the sleeve 103. The disk is fitted with a pin 119 which extends outwardly of the toothed clutch disk 101 and is slidably received in the slot 111 between the wings 113 on the disk 107 to drivingly interconnect the cam 115 with the switch tripping disk 107. The cam disk 115 is also fitted with a finger 121 in position to drivingly engage the ratchet teeth of the gear 101 when the same, which is fast on the shaft 85, is thrust toward the disk 115 by the action of the solenoid. The shaft 85 and the sleeves 103 and 117 extend within a support plate 123 which is mounted on pedestals 125 formed on the inner face of the plate 29, said plate 123 having a central opening in which the sleeve 117 is journaled in a fashion preventing relative axial movement of the sleeve 117 and the cam disk 115 carried thereby. The plate 123 also carries a lever 127 pivoted as at 129 near the margin of the plate, said lever having a roller 131 in position to engage the periphery of the asymmetrical heart shaped cam disk 115. Spring means 133 anchored at one end on a pin 135 near the edge of the plate 123, and fastened at its other end to the lever 127, is provided for normally and yieldably urging the roller 131 onto the disk whereby at all times to tend to rotate the disk to stand-by position illustrated in Figure 3 of the drawings and thus position the driving finger 121 and the switch tripping projection 109 in predetermined relative angular positions with respect to the axis of rotation of the disk 115, since the switch tripping disk 107 is drivingly connected therewith. It will be noted that through the foregoing expedient, the switch tripping projection 109 will always occupy the same starting position. The clutch disk or driving gear 101 preferably has a number of teeth selected in accordance with the number of fluctuations of the monitoring wave which elapse during one revolution of the gear so that, by adjusting the angularity of the motor in its support, the apparatus may be adjusted to open and close the switches always at the zero point of the monitoring wave; and in this connection, it may be noted that the successful operation of the device is not

dependent upon the maintenance of the frequency of the monitoring wave at an absolutely constant value. On the contrary, the timer is particularly adapted to perform regardless of frequency variations, the switches being closed and opened during time intervals determined as a function of the number of fluctuations of the monitoring wave elapsing during the switch closing and opening instants. The time intervals involved thus need not necessarily be constant functions of time, although they are constant functions of the frequency of the monitoring wave, which may vary, and may be constant functions of time where the frequency of the monitoring wave is maintained constant.

The switch members 45 both have actuating projections 137 comprising stems secured in the members 45 and extending radially inwardly in position to co-operate with the resetting collar 99 on the shaft 85. During the operation of the device, the solenoid 25 is actuated to project the shaft 85, the resetting collar 99, the switch tripping disk 107, and the driving gear 101 forwardly in the frame portion 99 into position such that the gear 101 drivingly engages the finger 121 on the cam member 115. When in such driving position, the resetting collar 99 is released from the switch resetting projections 137. Since the shaft 85 is in constant rotation, being driven by the motor 23 through the pinion 81 and gear 83, the driving connection established by engagement of the gear 101 with the finger 121 instantly starts the cam 115 in rotation at a rate of speed determined by the operating speed of the motor 23. Since the switch tripping disk 107 is drivingly connected with the cam 115, it also will be rotated in shifted position. It will be noted that when the disk 107 is in shifted position, its edge turns opposite the switch actuating members 139 which will be forced radially outwardly at the instant when the tripping projection 109 on the disk 107 successively passes the members 139 during rotation of the disk 107. Since the tripping finger 109 always starts from a relative position determined by the cam 115 and its follower 131, the normally open switch 11 will be closed by the engagement of the finger 109 with the actuating member 139 of said switch 11 after an interval required to move the finger 109 into engagement with the bolt 139 following actuation of the solenoid 25. Since the motor 23 operates at synchronous speed, this interval will always be equal to the time required for a constant number of fluctuations of the monitoring wave. By arranging the openings 65 in proper spacement in the plate 29, in accordance with the synchronous speed of the motor 23, it will be seen that the switch 15, or rather its actuating member 139, may be adjusted to any position representing a predetermined time interval in terms of fluctuations of the monitoring wave which controls the synchronous speed of the motor 23. The switch 15 thus may be arranged in adjusted position to allow for the elapse of any predetermined number of fluctuations of the monitoring current between the closure of the switch 11 and the opening of the switch 15 when its member 139 is thrown by the actuating finger 109.

The actuating finger 139 of each switch comprises a stem 141 axially shiftable in the sub-frame 41, the stem being provided with a roller at one end in position to engage the finger 109 and being pivotally connected at the other end, as at 143, with a switch releasing latch lever 145 which has an end pivoted as at 147 on the sub-

frame 41. Spring means 149 is provided to normally urge the stem 141 radially inwardly in a direction to present the roller carrying end thereof in the path of the switch tripping finger 109. 5 The pivot remote end of the latch lever 145 is provided with a pair of shoulders 151 and 153 providing successively acting catches, the shoulder 151 serving to hold the switch member 45 in reset position, reset position, in the case of switch 10 11 being open position and in the case of the switch 15 being closed position. To this end, the member 45 of each switch has means 155 forming a seat carrying a detent finger 157 and a spring anchorage neck 159, the finger 157 preferably 15 comprising a strip of sheet metal extending in position to engage the shoulder 151 of the latch 145. The spring anchorage neck 159 of the switch 15 is connected to one end of a spring 161, the other end of which is adjustably anchored on 20 a bracket 163 secured on the yoke 51, the neck and spring being arranged to urge the switch member 45 in a direction normally urging the switch 15 toward open position, the latch 145 serving to hold the switch closed against the influence of the spring 161. The spring anchorage neck 159 of the switch 11 is fastened to one end of a spring 165, the other end of which is adjustably secured on the frame 17, the neck and spring being arranged so that the spring normally urges 25 the switch member 45 toward closed position, the latch 145 in the switch 11 serving to hold the switch open against the influence of the spring 165.

The action of the resetting collar 99 under the 30 influence of the spring 95 is to press the switch fingers 137 in a direction to reset the switches, the switch 11 to open position and the switch 15 to closed position, against the influence of the springs 161 and 165. When reset, the switches 40 are held in cocked position by the engagement of the detent fingers 157 with the latch 145, which are held in latching position by the springs 149. When the shaft 85 is projected by actuation of the solenoid 25, the collar 99 will release the fingers 137 which, however, will remain in switch 45 cocked position, since the members 45 carrying the same will be latched as aforesaid. As the switches are successively tripped by the engagement of the finger 109 successively with the members 137 of the switches, outward movement of the stems 141 against the influence of the springs 149 will successively release the latched members 157 and permit the switch 11 first to close under the influence of the spring 165 and thereafter permit the switch 15 to open under the influence of the spring 161. The latch portions 153, however, limit the opening and closing movements of the switches 11 and 15 so that when the shaft 85 is shifted rearwardly by the spring 95 at the conclusion of the operating cycle of the device, thus releasing the driving connection between the finger 121 and the gear 101, the action of the resetting collar 99 on the fingers 137 will be to return the switch members 45 of the switches 11 and 15, respectively, to switch open and switch closed position with the detents 157 engaged in the latch portions 151.

In order that the switches 11 and 15, respectively, may close and open at zero points in the 70 monitoring wave, it is desirable to provide for adjusting the angularity of the motor 23 on the frame extension 21. To this end, the motor frame is provided with a groove 167, and the motor is secured on the frame by means of an annular clamp 75 169 having portions fitting in the groove 167.

The motor thus may be turned in its clamp in order to calibrate it to the mechanism whereby to cause the switch 11 to open at a desired point, namely, a zero point in the monitoring wave, and the openings 65 in the plate 29 may be arranged in position causing the switch 15 to open at corresponding zero points in the monitoring wave.

The connection panel 27 may carry conventional terminals for the motor supply conductors and for the conductors controlling the solenoid 25.

My present invention is particularly well adapted for controlling X-ray equipment used in making X-ray pictures in which the exposure is a direct function of the number of pulsations of alternating current energy supplied to the X-ray generator rather than a function of time. Although the apparatus of my present invention is a timing device and does operate to control electric circuits in terms of elapsed time, because the control interval between the closure of switch 11 and the opening of switch 15 is determined by the speed of the synchronous motor 23, however, time control is actually accomplished in terms of the number of fluctuations of the monitoring impulse which, when the device is used with radiographic equipment, is the alternating current power supplied to the X-ray generator. By means of the device of my present invention, therefore, I am able to time X-ray exposures exactly in terms of X-ray impulses delivered by the generator. The apparatus is extremely compact, is rugged and is relatively simple in construction and operation. It affords simplicity of control and facility of operation.

It is thought that the invention and its numerous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A timing device comprising a frame, a pair of biased switches supported in said frame, latch means to secure one switch in open and the other in closed position, and actuating means operable on said frame to actuate said latch means to release the open switch for closing movement under the influence of its bias and to release the closed switch for opening movement under the influence of its bias a predetermined interval after closure of the open switch.

2. A timing device comprising a frame, a pair of switches on said frame, said switches being biased one toward open and the other toward closed position, latch means to secure one switch in closed and the other in open position, each against the influence of its bias, and actuating means operable on said frame to actuate said latch means to release the open switch for closing movement under the influence of its bias and to release the closed switch for opening movement under the influence of its bias a predetermined interval after closure of the open switch.

3. A timing device comprising a frame, a pair of biased switches supported in said frame, control means normally retaining one switch in open and the other in closed position, each against the influence of its bias, said switches being adapted for connection in series to control

a circuit, actuating means operable to close the normally open switch and then open the normally closed switch after a predetermined interval following closure of the normally open switch, and means to reset said switches, respectively, in normally open and normally closed position.

4. A timing device comprising a frame, a pair of biased switches supported in said frame, control means normally retaining one switch in open and the other in closed position, each against the influence of its bias, said control means comprising a control member for each switch, said switches and their associated control members being adjustably spaced apart and operable the one to release the normally open switch for closure under the influence of its bias and the other to release the normally closed switch for opening movement under the influence of its bias, and actuating means operable at substantially constant speed to trip the control member of the normally closed switch at a predetermined instant after tripping the control member of the normally open switch.

5. A timing device comprising a frame, a pair of biased switches supported in said frame, control means normally retaining one switch in open and the other in closed position, a control member for each switch, said switches and their associated control members being adjustably spaced apart along the arc of a circle and operable the one to release the normally open switch for closure under the influence of its bias and the other to release the normally closed switch for opening movement under the influence of its bias, and actuating means including a switch actuating member movable in a circular path and operable at substantially constant speed to trip the control member of the normally closed switch at a predetermined instant after tripping the control member of the normally open switch.

6. A timing device comprising a frame, a normally open and a normally closed switch supported in said frame, switch actuating means including an actuating member turnable on said frame in a circular path about an axis, each switch having an associated switch operating control member extending in the path of said actuating member, means to support one of said switches and its associated control member in said frame for movement about said axis to adjust the angular spacement of said switch control members about said axis, and means to secure the switches and associated control members in angularly adjusted position.

7. A timing device comprising a frame, a normally open and a normally closed switch supported in said frame, switch actuating means including an actuating member turnable on said frame in a circular path about an axis, each switch having an associated switch operating control member extending in the path of said actuating member, one of said switches and its associated control member being fixed on said frame and means for supporting the other of said switches and its associated control member in said frame for movement about said axis to adjust the angular spacement of said switch control members about said axis, and means to secure the switches and associated control members in angularly adjusted position.

8. A timing device comprising a frame, a normally open and a normally closed switch supported in said frame, switch actuating means including an actuating member turnable on said frame in a circular path about an axis, each

switch having an associated switch operating control member extending in the path of said actuating member, a support yoke mounted in said frame for turning movement about said axis, one of said switches and its associated control member being supported on said yoke for movement therewith about said axis to adjust the angular spacing of said switch control members about said axis, and cooperating latch means on the yoke and frame and operable to secure the yoke in any selected one of a number of angularly adjusted positions about said axis whereby to support the switches and associated control members in adjusted angularly spaced relationship.

9. A timing device comprising a frame, a normally open and a normally closed switch supported in said frame, a control member for each switch, said switches and their associated control members being adjustably spaced apart in said frame, actuating means operable to cause closure of the normally open switch and thereafter to cause opening of the normally closed switch, said actuating means being operable at substantially constant speed to trip the control member of the normally closed switch at a predetermined instant after tripping the control member of the normally open switch, means to secure said switches and associated control members adjustably in spaced position comprising index means on said frame, carrier means movable on said frame with respect to said index means and connected with one of said switches and its control member, co-operating latch means formed on the carrier and index means to latchingly secure the same in any selected one of a plurality of adjusted positions, and indicator means on said carrier and index means and comprising a scale on one and an indicating element on the other for showing the adjusted position of the parts.

10. A timing device comprising a frame, a normally open and a normally closed switch supported in said frame, a control member for each switch, said switches and their associated control members being adjustably spaced apart in said frame, actuating means operable to cause closure of the normally open switch and thereafter to cause opening of the normally closed switch, said actuating means being operable at substantially constant speed to trip the control member of the normally closed switch at a predetermined instant after tripping the control member of the normally open switch, means to secure said switches and associated control members adjustably in spaced position comprising index means on said frame, carrier means movable on said frame with respect to said index means and connected with one of said switches and its control member, co-operating latch means formed on the carrier and index means to latchingly secure the same in any selected one of a plurality of adjusted positions, and indicator means on said carrier and index means and comprising a scale on one and an indicating element on the other for showing the adjusted position of the parts.

11. A timing device comprising a frame, a normally open and a normally closed switch supported in said frame, a control member for each switch, said switches and their associated con-

5 trol members being adjustably spaced apart in said frame, actuating means operable to cause closure of the normally open switch and thereafter to cause opening of the normally closed switch, said actuating means being operable at substantially constant speed to trip the control member of the normally closed switch at a predetermined instant after tripping the control member of the normally open switch, means to secure said switches and associated control members adjustably in spaced position comprising index means on said frame, carrier means movable on said frame with respect to said index means and connected with one of said switches and its control member, co-operating latch means formed on the carrier and index means to latchingly secure the same in any selected one of a plurality of adjusted positions, a motor adapted to be driven under the control of a monitoring wave of electrical power fluctuating at a predetermined frequency, means to drivingly connect the motor with said actuating means, said adjusted positions corresponding with time intervals between closure of one switch and opening of another in terms of the frequency of the monitoring wave, and means to support and secure said motor in precisely angulated position on said frame whereby to cause actuation of said switches at desired instances during the progress of said monitoring wave.

30 12. A timing device comprising a frame, a normally open and a normally closed switch on said frame, a control member for each switch, means to support said switches and their associated control members in adjusted angularly spaced position in said frame, said control members being operable the one to cause closure of the normally open switch and the other to cause opening of the normally closed switch, actuating 35 means supported in said frame including a switch actuating member movable in a circular path about a rotary axis and operable at substantially constant speed to actuate the control member of the normally closed switch at a predetermined instant after actuating the control member of the normally open switch, said switch actuating member being normally stationary under standby conditions, a motor operable at a controlled speed, and means operable to drivingly connect 40 said actuating member with said motor to start the timing device in operation and to disconnect the member from the motor at the conclusion of the operating cycle of the device.

45 13. A timing device comprising a frame, a normally open and a normally closed switch on said frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable 50 in a circular path about said rotary axis and operable at substantially constant speed to actuate the control member of the normally closed switch at a predetermined instant after actuating the control member of the normally open switch, 55 said switch actuating member being normally

stationary under stand-by conditions, a motor operable at a controlled speed, means operable to drivingly connect said actuating member with said motor to start the timing device in operation and to disconnect the member from the motor at the conclusion of the operating cycle of the device, and means co-operatively associated with said member and, when the same is disconnected from the motor, normally urging it to stand-by position having a predetermined angular relationship with respect to the switch control member of the normally open switch.

14. A timing device comprising a frame, a normally open and a normally closed switch on said frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, means operable to drivingly connect said actuating member with said motor to start the timing device in operation and to disconnect the member from the motor at the conclusion of the operating cycle of the device, and a heart cam and spring-pressed follower drivingly connected with said member whereby, when the same is disconnected from the motor, to normally urge the member to stand-by position having a predetermined angular relationship with respect to the switch control member of the normally open switch.

15. A timing device comprising a frame, a normally open and a normally closed switch on said frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, and means operable to drivingly connect said actuating member with said motor to start the timing device in operation comprising a shaft drivingly connected with said motor and supporting said member, clutch means

operable to drivingly connect the shaft with said member, and means to shift the shaft axially in one direction to operate the clutch.

16. A timing device comprising a frame, a normally open and a normally closed switch on said frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, and means operable to drivingly connect said actuating member with said motor to start the timing device in operation comprising a shaft drivingly connected with said motor and supporting said member, clutch means operable to drivingly connect the shaft with said member, and means to shift the shaft axially in one direction to operate the clutch means, said clutch means comprising a gear member and a co-operating tooth member connected one on the shaft and the other to the switch actuating member.

17. A timing device comprising a frame, a normally open and a normally closed switch on said frame, a control member for each switch means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, and means operable to drivingly connect said actuating member with said motor to start the timing device in operation and to disconnect the member from the motor at the conclusion of the operating cycle of the device, comprising a shaft drivingly connected with said motor and supporting said member, clutch means operable to drivingly connect the shaft with said member, means to shift the shaft axially in one direction to operate the clutch means, and yielding means normally urging the shaft axially in the opposite direction toward stand-by position.

18. A timing device comprising a frame, a normally open and a normally closed switch on said

frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, and means operable to drivingly connect said actuating member with said motor to start the timing device in operation and to disconnect the member from the motor at the conclusion of the operating cycle of the device, comprising a shaft drivingly connected with said motor and supporting said member, clutch means operable to drivingly connect the shaft with said member, means to shift the shaft axially in one direction to operate the clutch means, and yielding means normally urging the shaft axially in the opposite direction toward stand-by position, said switches each having resetting means extending adjacent said shaft and said shaft having means thereon to engage and actuate said resetting means when moved to stand-by position.

19. A timing device comprising a frame, a normally open and a normally closed switch on said frame, a control member for each switch, means to support said normally open switch and its associated control member in fixed position in said frame, means to support the normally closed switch and its associated control member adjustably for angular movement about an axis of rotation in said frame whereby said control members may be adjustably spaced apart along the arc of a circle centred at said axis, said control members being operable the one to cause closure of the normally open switch and the other to cause opening of the normally closed switch, actuating means supported in said frame including a switch actuating member movable in a circular path about said rotary axis and operable at substantially constant speed to actuate the control member of the normally closed switch at a predetermined instant after actuating the control member of the normally open switch, said switch actuating member being normally stationary under stand-by conditions, a motor operable at a controlled speed, and means operable to drivingly connect said actuating member with said motor to start the timing device in operation and to disconnect the member from the motor at the conclusion of the operating cycle of the

device, comprising a shaft drivingly connected with said motor and supporting said member, clutch means operable to drivingly connect the shaft with said member, means to shift the shaft axially in one direction to operate the clutch means, and yielding means normally urging the shaft axially in the opposite direction toward stand-by position, said switches each having resetting means extending adjacent said shaft and said shaft having means thereon to engage and actuate said resetting means when moved to stand-by position.

20. A timing device comprising a frame, a normally open and a normally closed switch adapted for connection in series to control a circuit, means to mount said switches in spaced relationship in said frame, actuating means operable on said frame to close the normally open switch and then open the normally closed switch after a predetermined interval following closure of the normally open switch, said switches each comprising a support base carrying a fixed contact element, a movable switch member shiftable on said base and carrying a movable contact member in position to engage and release said fixed contact element whereby the switch may selectively assume switch open and switch closed position, a latch comprising a tiltable detent keeper on said base and a detent on said movable member adapted to latch with said keeper to hold said movable member normally in one of said switch positions, and yielding means biasing said movable switch member toward and operable to throw the movable switch member to the other switch position upon release of said keeper from the detent by operation of said actuating means.

21. A timing device comprising a frame, a normally open and a normally closed switch adapted for connection in series to control a circuit, means to mount said switches in spaced relationship in said frame, actuating means operable on said frame to close the normally open switch and then open the normally closed switch after a predetermined interval following closure of the normally open switch, said switches each comprising a support base carrying a fixed contact element, a movable switch member shiftable on said base and carrying a movable contact member in position to engage and release said fixed contact element whereby the switch may selectively assume switch open and switch closed position, a latch comprising a tiltable detent keeper on said base and a detent on said movable member adapted to latch with said keeper to hold said movable member normally in one of said switch positions, and yielding means biasing said movable switch member toward and operable to throw the movable switch member to the other switch position upon release of said keeper from the detent by operation of said actuating means, said movable switch member having a resetting member operable to shift the movable switch member against the influence of said yielding means to latch the detent with the keeper.

ARTHUR J. KIZAUR.
